UNITED STATES PATENT OFFICE.

CLARENCE E. CUNDEY, OF PHILADELPHIA, PENNSYLVANIA.

FIBER-HEAD SPOOL.

Application filed May 8, 1924. Serial No. 711,758.

My invention relates to spools used for winding textile threads as well as wires, and it relates more particularly to the type of spool used for high speed winding, having 5 a hollow barrel of wood and fiber heads or ends.

It has heretofore been the practice to secure the fiber ends to the hollow wooden barrel, by means of wooden thimbles having an 10 outside diameter equal to the inside diameter of the bore of the barrel, and having a flange of substantially the same diameter as the outside of the barrel. The body of the thimble was passed through a hole of the 15 same diameter in the fiber head and was then driven and glued into the barrel. In addition to this, a wooden peg was passed transversely through one wall of the barrel at each end, into the body of the thimble, to 20 prevent the thimbles, and hence the spool heads, from working loose.

This construction has the disadvantage in that when the heads do work loose in time, there is no means of tightening them, and 25 when the bearing holes in the thimbles, or any other part of the spool wears, there is no practical way of replacing the worn part, and the whole spool must thus be discarded.

The novel construction embodying my in- 30 vention eliminates the above disadvantages by providing a thimble which is readily removable, thus permitting the replacement of the spool heads as well as the thimbles, and whereby any play between the barrel and the 35 heads may be taken up by simply turning the thimble. My novel construction further provides a bearing hole which will have better wearing qualities, particularly when used at high speed, under which conditions 40 a wooden bearing will not stand up for any length of time.

With the above ends in view my novel fiber head spool consists of a hollow cylindrical barrel preferably of wood, having its bore 45 threaded a certain distance at both ends, a fiber head at each end, and an externally threaded, flanged thimble, preferably of metal, adapted to engage the threads in the barrel, and secure the heads to the barrel.

50 For the purpose of illustrating my invention I have shown in the accompanying drawings one form thereof which is at present preferred by me, since the same has been found in practice to give satisfactory and reliable results, although it is to be understood 55 that the various instrumentalities of which

my invention consists can be variously arranged and organized and that my invention is not limited to the precise arrangement and organization of the instrumentalities as herein shown and described. 60

Fig. 1 represents a perspective view of the novel construction in spools embodying my invention.

Fig. 2 represents a section on line 2—2 of 65 Fig. 1.

Referring to the drawings, 1 designates the cylindrical barrel of my novel spool construction, having a concentric opening 2 extending longitudinally therethrough, and 70 having the two ends thereof threaded as at 3. To the ends of the barrel I secure the two fiber heads 4 by means of the flanged thimbles 5 having their threaded body portions 6 turned into the ends of the barrel. 75 The flanges 7 are provided with a plurality of recesses 8 for the reception of the prongs of a sprocket wrench. In order to prevent the heads 4 from turning, I provide the pins 9 therethrough, driven into the body of the 80 barrel 1. The felt washers 10 are provided to give a better joint between the fiber discs 4 and the barrel 1.

The thimbles may be made of any suitable material, so as to provide a good wearing 85 and frictionless bearing surface 11; although in the preferred embodiment of my invention the thimbles are made of some light and anti-friction metal or alloy such as aluminum or white metal. 90

It will now be apparent that I have devised a novel and useful construction which embodies the features of advantage enumerated as desirable in the statement of the invention and the above description and 95 while I have in the present instance shown and described the preferred embodiment thereof which has been found in practice to give satisfactory and reliable results, it is to be understood that the same is susceptible 100 of modification in various particulars without departing from the spirit or scope of the invention or sacrificing any of its advantages.

Having thus described my invention, what 105 I claim as new and desire to secure by Letters Patent, is:

In a spool of the character stated, a tubular barrel having internal threads in the terminal portions of the bore thereof, a removable terminal fiber head at each end of 110 said barrel having a central aperture in

alignment with the bore of said barrel, locking pins passing through each of said fiber heads and into the terminals of said barrel, a metallic bearing thimble at each end of 5 said spool having an externally threaded tubular portion extending through the central aperture in the respective fiber head and extending into and threadedly engaging the internally threaded terminal portions of the 10 bore of said barrel and having an external terminal flange formed integrally with the

tubular portion of said thimble overhanging and engaging the inner peripheral edge portion of the respective fiber heads to clamp the same endwise to the barrel and overlapping and locking the outer terminals of the respective pins, and a resilient washer interposed between each end of said barrel and the corresponding fiber head. 15

In testimony whereof, I have hereunder signed my name. 20

CLARENCE E. CUNDEY.
